UNITED STATES PATENT OFFICE.

WILLIAM G. CONN, OF CHARLESTOWN, INDIANA.

WATCHMAKER'S TWEEZERS.

SPECIFICATION forming part of Letters Patent No. 660,489, dated October 23, 1900.

Application filed October 7, 1899. Serial No. 732,934. (No model.)

To all whom it may concern:

Be it known that I, WILLIAM G. CONN, a citizen of the United States, residing at Charlestown, in the county of Clark and State of Indiana, have invented a new and useful Watchmaker's Tool, of which the following is a specification.

This invention relates to watchmaker's tools, and has for its object to provide an improved implement which is capable of gripping either of the plates of the watch-movement and at the same time holding one of the parts of the latter, so that the plate and the said part of the movement may be simultaneously placed in position, so as to facilitate the assembling of the parts of the movement to preserve the relative arrangement thereof and to prevent breaking of pivots and other fragile parts. It is especially designed for positioning the escapement-lever so as to insure the proper arrangement and to prevent breaking of the pivots thereof.

To these ends the present invention consists in the combination and arrangement of parts, as will be hereinafter more fully described, shown in the accompanying drawings, and particularly pointed out in the appended claims, it being understood that changes in the form, proportion, size, and minor details of construction may be made within the scope of the appended claims without departing from the spirit or sacrificing any of the advantages of the invention.

In the drawings, Figure 1 is a top plan view of a top plate of a watch-movement having the present implement applied thereto and holding a part of an escapement-lever. Fig. 2 is a perspective view of a tool constructed in accordance with the present invention. Fig. 3 is a transverse sectional view taken through the pivotal or hinged connection between the parts of the tool. Fig. 4 is a longitudinal central sectional view of the tool. Fig. 5 is a plan view of the intermediate member thereof.

Corresponding parts in the several figures of the drawings are designated by like characters of reference.

Referring to the drawings, the present tool comprises opposite outer members or levers 1 and 2, respectively, and an intermediate lever or member 3, of which one of the outer

members and the intermediate member are of substantially the same length, and the other outer member is shorter than either of the former members. All of the members have a common pivotal or hinged connection 4, located intermediate of the ends thereof, so that they are adapted to be rocked upon a common center.

At one and the same side of the pivotal connection each member is formed into a clamping-jaw 5, and at its opposite end is enlarged to form a finger plate or piece 6, which is serrated or roughened upon its outer face to facilitate gripping the plate.

Fastened to the inner side of the finger-plate of each outer member is a leaf-spring 7, which is bowed inwardly and toward the pivotal connection of the members and has its free inner end frictionally engaging the adjacent side of the intermediate member, so as to close or normally hold together the opposite outer ends of the several jaws 5. By this arrangement all of the jaws may be opened or spread apart by pressing inwardly upon the finger-plates of the outer members, and the longer or top member may be opened independently of the lower short member by pressing upon the finger-plates of the outer longer member and the adjacent intermediate member.

To form the pivotal connection between the members, each of the latter is provided with a central lateral enlargement 8, carrying bearing-ears, which are hingedly connected by means of a pivot-pin 9. As shown in Fig. 3, the upper member 1 is provided with a pair of pendent spaced ears 10, each of which is located inward from the adjacent longitudinal edge of the member. The opposite lower or outer member 2 is provided with a central upstanding ear 11, which is located intermediate of the ears of the member 1. The intermediate member is provided with a pair of ears 12, which are located at opposite edges of the enlarged portion of the member and project equally at opposite sides thereof and at substantially right angles to the plane of the member. Provided centrally of the enlargement of the intermediate member, as shown in Fig. 5, is an opening or perforation 13 for the reception of the ears of the other members, those of the upper mem-

ber 1 being inserted from one side of the intermediate member and those of the other member 2 being inserted from the other side of the said intermediate member, all of the 5 ears fitting closely together and hingedly connected by the pivot-pin 9. One end of the latter is screw-threaded, as at 14, so as to be fixedly fitted into a correspondingly-threaded opening 15 in one of the ears of the intermediate member, and the opposite end of the pivot-pin is provided with a head 16, which is countersunk in the outer side of the opposite ear of the member and provided with a suitable screw-driver slot for applying and 15 removing the pivot-pin.

In the operation of the tool a part 17 of the watch-movement, such as the escapement-lever, is picked up between the outer member 2 and the intermediate member. The 20 tool is then applied to the top plate 18, the latter being received between the upper or outer member 1 and the adjacent side of the intermediate member. This application of the tool is had by reason the independent operation of the members thereof, as hereinbefore set forth. Thus it will be seen that the part 17 is held between a pair of the members, and the entire tool is held to the plate by the intermediate member and the other outer 25 member. The part 17 and the plate may be then simultaneously fitted to the watch-movement, thereby preserving the relative position of the parts and preventing the pivots of the lever from becoming broken. After 30 the part and the plate have been placed in position the tool may be removed by pressing the outer members together, which will open all of the jaws, so as to release the part 17 and also disengage the tool from the plate.

40 Having thus described the invention, what is claimed, and desired to be secured by Letters Patent, is—

1. A watchmaker's tool comprising an intermediate member having an outer engag-

ing portion and an inner handle portion, and 45 the oppositely-disposed spring-pressed outer members having inner handle portions and outer engaging portions, one of the outer members being shorter than the intermediate member, whereby the said outer members are 50 adapted to be operated independently of each other to permit one of the plates and one of the other parts of a watch-movement to be independently gripped and simultaneously held and placed in position, substantially as 55 described.

2. A watchmaker's tool, comprising opposite outer spring-pressed members, and an intermediate member, each outer member being located entirely at its respective side of 60 the intermediate member, all of the members having a common intermediate pivotal connection, forming jaws normally in mutual engagement, and operating finger-pieces for the respective jaws, the intermediate finger-piece 65 being longer than one of the outer finger-pieces, and the outer members being independently movable out of engagement with the intermediate member.

3. A watchmaker's tool, comprising opposite outer members, an intermediate member, each outer member being located entirely at its respective side of the intermediate member, a common pivotal connection for all of the members, forming jaws in mutual engagement, and finger-pieces for the respective jaws, the intermediate finger-piece being longer than one of the outer finger-pieces, and opposite springs interposed between the intermediate finger-piece and the respective 75 outer finger-pieces.

In testimony that I claim the foregoing as my own I have hereto affixed my signature in the presence of two witnesses.

WILLIAM G. CONN.
